UNITED STATES PATENT OFFICE.

EDWIN GEDCKE, OF KINDERSLEY, SASKATCHEWAN, CANADA.

PLOWSHARE.

1,234,006.

Specification of Letters Patent. Patented July 17, 1917.

Application filed September 10, 1915. Serial No. 50,027.

To all whom it may concern:

Be it known that I, EDWIN GEDCKE, a subject of the King of Great Britain, residing at Kindersley, in the Province of Saskatchewan and Dominion of Canada, have invented new and useful Improvements in Plowshares, of which the following is a specification.

The invention relates to plows and it has 10 particular reference to an improved method of attaching the share to the mold board and land side of an ordinary plow.

The customary method of attaching shares is by means of bolts or rivets. When 15 shares are to be detached for sharpening or other purposes rivets are manifestly objectionable, while bolts are liable to become rusted, thereby making the detachment of the nuts difficult. The object of the present 20 invention is therefore to devise a novel and improved method of attaching the share whereby the objections heretofore existing will be entirely overcome.

A further object of the invention is to so 5 connect the share with the mold board and land side of a plow that it may be instantly detached without the use of tools of any kind.

A further object of the invention is to devise 0 a method of mounting shares by which the use of bolts, rivets or other like permanent fastening means will be avoided.

With these and other objects in view, the invention consists in the improved construction, arrangement and combination of parts which will be hereinafter fully described and particularly pointed out in the claims.

In the drawings hereto annexed has been illustrated a simple and preferred form of the invention; it being, however, understood that no limitation is necessarily made to the precise structural details therein exhibited, but that changes, alterations and modifications within the scope of the appended claim may be resorted to when desired.

In the drawing:—

Figure 1 is a top plan view of a portion of a plow embodying the invention.

Fig. 2 is a bottom plan view of the same.

Fig. 3 is a detail bottom plan view of the share detached.

Fig. 4 is a detail bottom plan view showing a portion of the mold board and land side detached.

Fig. 5 is a sectional detail view taken on the line 5—5 in Fig. 2.

Fig. 6 is a detail side view of a portion of the plow as seen from the land side.

Corresponding parts in the several figures are denoted by like characters of reference.

The mold board, a portion of which is shown at 15, is of ordinary construction, said mold board being connected with the land side, a portion of which appears at 16. Permanently secured on the inner face of the land side is a connecting plate 17 which in practice lies adjacent to the inner face of the land side member 18 associated with the share 19 which latter, as will be seen, is of ordinary contour and general construction. 60 The land side member 18 is provided with one or more pins or pegs 20 projecting inwardly so as to engage corresponding apertures or perforations 21 in that portion of the connecting plate 17 which lies adjacent to the land side member 18. The mold board 15 is provided on its under side with an arcuate lug or projection 22 which is fixedly attached thereto and which projects beyond the edge of the mold board in the 65 direction of and beneath the share 19 which latter is provided with a keeper 23 for the reception of said lug or projection.

The pins or pegs 20 are preferably so arranged that their inner ends will point somewhat in the direction of the mold board, or the said pins or pegs may be slightly arcuate for convenience in assembling the parts.

In the operation of this invention the 70 share may be assembled with the mold board by simply placing the pins 20 in engagement with the apertures 21 and at the same time guiding the lug or projection 22 into the keeper 23. Owing to the arcuate shape of 75 the lug it will, by engagement with the wall of the keeper, be pressed in the direction of the land side member 18 while it is being inserted into the keeper, thereby causing the pins or pegs extending from said land side 80 member to enter the apertures 21. When the lug or projection 22 has been pressed home in the keeper the parts will be found to have been practically assembled for working purposes, it being obvious that the strain 85 exerted by the soil against the share when the plow is in operation will tend to increase the security of the connection. On the other hand, to disassemble the parts, it is only necessary to take hold of the wing of the 90 share and to pull the latter forwardly, when the share will become readily detached.

Having thus described the invention what is claimed is:—

- A plow bottom comprising a mold board having a permanent landside member, a coupling plate secured to the inner face of said landside member and extending forwardly with respect thereto, said coupling plate having several apertures, an arcuate lug fixed on the underface of the mold board and projecting forwardly therefrom, and a share having a keeper to receive said arcuate lug, said share having also a landside member provided with pins that are curved in

the direction of the keeper which receives the arcuate lug, said pins engaging the apertures in the coupling plate on which the landside member of the share abuts in alignment with the landside member of the mold board. 15

In testimony whereof I affix my signature 20 in presence of two witnesses.

EDWIN GEDCKE.
